(57) **CLAIM**

The ornamental design for a drum ring, as shown and described.

DESCRIPTION

FIG. 1 is a perspective view of a drum ring showing my new design;

FIG. 2 is a top view of a drum ring showing my new design; FIG. 3 is a side view of a drum ring showing my new design; and,

FIG. 4 is another side view of the drum ring showing my new design.

The broken lines in FIGS. 1-4 illustrate environmental structure and form no part of the claimed design.
